Patented Feb. 23, 1971

220,022

COMBINED WALLET AND CHANGE PURSE

Henry C. White, Springfield, N.J. (½ Specialty Leather Goods, Inc., 440 Lafayette St., New York, N.Y. 10003)

Filed Mar. 18, 1970, Ser. No. 21,960

Term of patent 14 years

Int. Cl. D3—02

U.S. Cl. D87—3

FIG. 1

FIG. 2

FIG. 3

FIG. 4

FIG. 1 is a front elevational view of a combined wallet and change purse showing my new design;

FIG. 2 is a rear elevational view thereof;

FIG. 3 is a side elevation thereof; and

FIG. 4 is a perspective view thereof in an open condition.

I claim:

The ornamental design for a combined wallet and change purse, as shown.
